JOINT SERVICE COMMENDATION MEDAL

Stafford F. Potter, Arlington, Va., assignor to the United States of America as represented by the Secretary of the Army

Filed July 20, 1964, Ser. No. 80,938

Term of patent 14 years

(Cl. D29—19)

(Granted under Title 35, U.S. Code (1952), sec. 266)

FIG. 1

FIG. 3

FIG. 2

FIG. 1 is a front elevational view of a joint service commendation medal, showing my new design; FIG. 2 is a rear elevation thereof; and

FIG. 3 is a side elevation thereof.

The essential features of my design are shown in solid lines.

The design described herein may be reproduced and used by or for the Government for governmental purposes without the payment to me of any royalty thereon.

I claim:

The ornamental design for a joint service commendation medal, as shown and described.
